CLAIM

The ornamental design for a cart for a bowling ball bag, as shown and described.

DESCRIPTION

FIG. 1 is a rear perspective view of a cart for a bowling ball bag showing my new design;

FIG. 2 is a rear elevational view thereof;

FIG. 3 is a front elevational view thereof;

FIG. 4 is a side elevational view thereof viewed from the left side of FIG. 3;

FIG. 5 is a side elevational view thereof viewed from the right side of FIG. 3;

FIG. 6 is a top view thereof; and

FIG. 7 is a bottom view thereof.

The broken lines shown in the drawing are for illustrative purposes only and form no part of the design.

FIG. 1

FIG. 2

FIG. 3

FIG. 4
